UNITED STATES PATENT OFFICE.

WILLIAM L. BURNER, OF KOPPEL, AND OSCAR E. KANTENWEIN, OF NEW CASTLE, PENNSYLVANIA, ASSIGNEES TO KOPPEL INDUSTRIAL CAR AND EQUIPMENT COMPANY, OF PITTSBURGH, PENNSYLVANIA, A CORPORATION OF PENNSYLVANIA.

DUMP CAR.

Application filed September 11, 1924. Serial No. 737,028.

This invention relates to railway dump cars, and more particularly to that type of dump car having a tilting body and has for an object the provision of a hinge for the body of such car which will permit a maximum tipping of the body and at the same time will cause the body to move to the side a sufficient distance to dump lading carried by the car free of the railroad track rails. 5 Another object of the invention is to provide a hinge for the tilting body of a railway car which will permit the free tilting and sidewise movement of the body but which will not become accidentally disconnected. 10

A further object of the invention is to provide a hinge for the tilting body of a railway dump car which is simple in construction, easy to assemble and disassemble 20 and yet will not become accidentally separated.

These and other objects will be apparent from the following description.

Referring to the drawings in which like reference characters refer to like parts, Fig. 25 1 is a cross sectional view of a railway dump car embodying the invention; Fig. 2 is an enlarged cross sectional view of a portion of the car showing the invention; Fig. 3 is 30 a side elevational view of a portion of the car, showing the invention applied thereto and Fig. 4 is a sectional view of the same taken on the line 4-4 of Fig. 3.

Referring now in detail to the drawings, 35 the reference character 1 indicates the underframe of the car and 2 the car body which body is mounted on the underframe in such a manner that it can be tilted to one side or the other to discharge the lading 40 carried thereby.

The underframe and body may be of any suitable construction and are connected together through the medium of hinges 3 which hinges permit the body to tilt and 45 move bodily toward one side or the other.

Each of the hinges 3 comprises a part 4 which is secured to the underframe and a part 5 which is secured to the car body. The part 4 extends upwardly from the 50 underframe and the upper outer surface thereof is provided with a centrally arranged depression 6. At each end this part is provided with an outwardly projecting portion 7 having a curved bearing surface.

8 at its lower end and outwardly curved 55 bearing surfaces 9 extending upwardly therefrom and terminating in notched or bearing surfaces 10 the purpose of which will be hereinafter fully set forth.

The part 5 depends downwardly from the 60 body of the car and is provided with spaced lower portions 11 having inwardly extending lugs 12 adjacent their lower ends. Some distance above these lugs 12 a web 13 is provided which extends between the 65 spaced portions 11 and at its sides 14 is curved downwardly to correspond with the shape of a curved surface 15 of the part 4. Below the web 13 a pin 16 is provided which extends between and through the spaced 70 portions and is adapted to seat in the depression 6 in the part 4. The lugs 12 on the spaced portions 11 are adapted to engage the bearing surfaces 8, 9 and 10 of the part 4 when the body of the car is operated. 75

When the car body is in its righted or normal position the pin 16 of the part 5 is seated in the depression 6 of the part 4 and the lugs 12 of the part 5 are in engagement 80 with the curved bearing surfaces 8 of the part 4 and this pin supports the body and any weight carried thereby.

Assuming the car body being tipped or moved to one side toward discharging position from its righted or normal position, the 85 pin 16 of the part 5 forms an axis around which the body rotates until such time as one of the curved surfaces 15 of the part 4 is engaged by one of the curved surfaces 14 of the part 5. When these surfaces engage, 90 the lugs 12 on the part 5 will have moved from the bearing surface 8 of the part 4 to the curved bearing surface 9 of this part and the weight of the body will have been transferred from the pin 16 to the parts 95 4 and 5 directly and a continued movement of the car body will cause the body and pin 16 to be elevated to some extent and moved laterally at the same time from the longitudinal center line of its normal or righted 100 position until the lugs 12 engage the surface 10 which is in the form of a notch, at which time the movement of the body will be stopped by suitable shock absorbing devices secured to the underframe not shown in the drawings. It will be noted that the lugs 12 105 due to their engagement with the surfaces 10 and the pin 16 which engages the upper

portion of the part 4 will prevent the body from moving laterally free of the under-frame. When the car is being righted the operation of the hinge is the reverse of that just described or when the car body is being dumped to the opposite side the operation will be the same as that described.

In applying this hinge the part 5 is moved in a direction transversely of the car over 10 the part 4 until the openings in the lower portions 11 of the parts 5, through which the pin 16 passes, register with the depression 6 in the part 4, in which position the pin is inserted in one of the openings and moved lengthwise through the depression 6 and into the other opening in the part 5. When the pin is in its proper position, the ends thereof extend beyond the portions 11 and to prevent accidental movement of the 20 pin, cotters 17 are provided which pass through the pin and are adapted to engage the portions 11.

Having thus described the invention, what we claim as new and desire to secure by 25 Letters Patent is:—

1. In a dump car, an underframe, a tilting body, a hinge for said body comprising a stationary part attached to said underframe and a movable part attached to said 30 body, means on said movable part adapted to engage with said stationary part to form a pivot during a partial tipping of said body, means on said parts adapted to cooperate to move said first mentioned means out of its 35 pivotal position during the rest of the tipping movement of said body, and means for preventing the separation of said parts.

2. In a dump car, an underframe, a tilting body mounted on said underframe, a 40 hinge for said body comprising means for supporting said body and for forming a pivot for said body during the partial tipping thereof, means on said hinge for transferring the weight of said body from the first mentioned means to the second mentioned means during the rest of the tipping movement of said body, and means for preventing the separation of said hinge.

3. In a dump car, a supporting frame, a 50 car body mounted on said frame to tilt, a hinge for said body comprising a stationary part secured to said underframe and a movable part secured to said body, a pin in said movable part adapted to engage with said stationary part to form a pivot for said body during a partial tipping of said body, means on said parts adapted to cooperate to move said body and pin upwardly and outwardly during the rest of the tilting movement, and means for preventing the separation of said parts.

4. In a dump car, an underframe, a tilting body, a hinge comprising a stationary part and a movable part, a pin in said movable part adapted to engage said stationary part to form a pivot for said body during the partial tipping thereof, means on said movable part adapted to engage said stationary part as said body is tipped, whereby said pin is moved out of pivotal engagement 70 with said stationary part for the rest of the tipping movement of said body, and means for preventing the separation of said parts.

5. In a dump car, an underframe, a tilting body, and a hinge comprising a movable part and a stationary part, said movable part having means adapted to engage said stationary part to form a pivot for said body during a partial tipping thereof, said parts being adapted to cooperate above said 80 means to form a pivot for said body during the rest of the tipping movement and to move said body outwardly, and means for preventing the separation of said parts.

6. In a dump car, an underframe, a tilting body, a hinge for said body comprising a stationary part secured to said underframe, and a movable part secured to said body, said parts comprising a plurality of pivots for said body, one of said pivots being arranged above and at one side of the other of said pivots, and means for locking said parts together against accidental separation.

7. In a dump car, a tilting body and a hinge for said body, said hinge comprising a stationary part, a movable part adapted to overlap said stationary part, a member on said movable part adapted to engage the upper surface of said stationary part, means on said movable part below said member adapted to engage said stationary member to prevent the separation of said parts.

8. In a dump car, an underframe, a tilting body and a hinge for said body, comprising a stationary part secured to said underframe, and a movable part secured to said body, said parts being adapted to cooperate to form a plurality of pivots for said body whereby said body may be tipped and moved away from the longitudinal center line of the car, there being surfaces on said stationary member corresponding in shape to the path of movement of said movable member as said body is tipped, and lugs on said movable member adapted to engage said surfaces to prevent the separation of said parts.

In testimony whereof, we affix our signatures.

WILLIAM L. BURNER.
OSCAR E. KANTENWEIN.
